UNITED STATES PATENT OFFICE.

CHARLES E. SCRIBNER, OF CHICAGO, ILLINOIS, ASSIGNOR TO THE WESTERN ELECTRIC COMPANY, OF SAME PLACE.

DERIVED CIRCUIT FOR CLEARING-OUT ANNUNCIATORS.

SPECIFICATION forming part of Letters Patent No. 300,144, dated June 10, 1884.

Application filed February 25, 1884. (No model.)

To all whom it may concern:

Be it known that I, CHARLES E. SCRIBNER, a citizen of the United States, residing at Chicago, in the county of Cook and State of Illinois, have invented a certain new and useful Improvement in Derived Circuits for Clearing-Out Annunciators of a Telephone-Exchange, (Case 73,) of which the following is a full, clear, concise, and exact description, reference being 10 had to the accompanying drawings, forming a part of this specification.

My invention relates to switch-board apparatus for telephone-exchanges.

In a prior application for Letters Patent, filed by me November 20, 1883, for improvement in "operator's apparatus for telephone switch-boards," I have shown and described apparatus for connecting together any two subscribers of a telephone-exchange, with 20 mechanism adapted to connect the operator's telephone-outfit into the circuit of the connected subscribers by the same act which disconnects the clearing-out drop from said circuit. By this arrangement the resistance of 25 only one of the instruments is in the circuit of the subscribers' connected lines at any time. This arrangement, while entirely practical, has some defects which I have sought to overcome by the present invention, hereinafter described. First, in connecting in one instrument and disconnecting the other, the circuit is for an instant broken, and in case the switch or connecting mechanism should for any reason fail to make contact the circuit would be 30 left open; second, the circuit of the connected subscribers always contains the contact-points of the connecting mechanism, which are liable to become corroded, thereby adding to the resistance of the circuit.

My present invention consists in placing the clearing-out drop permanently in circuit between the connecting-plugs, and providing mechanism whereby the operator's outfit may be looped around the clearing-out drop, as 45 hereinafter described and claimed.

In the accompanying drawings, Figure 1 is a diagram of circuits and apparatus embodying my invention. Fig. 2 is a diagram view of a single pair of connecting-plugs, and the 50 circuit between them.

Like parts are indicated by similar letters of reference in the different views.

A represents a switch-board, to which any suitable number of subscribers' lines, *a b*, may be connected. These lines may be connected through suitable switches, *a' b'*, and calling-annunciators *a² b²* to ground in the usual way. A connection between two subscribers is preferably made by means of the connecting-plugs *c d*, arranged in pairs, and provided with the usual conducting-cords, *c' d'*. Each pair of plugs has connected permanently in circuit therewith a clearing-out annunciator, *e*, as shown in Fig. 2, and indicated by dotted lines *f* in Fig. 1. The annunciator *e* is connected 65 on either side with the springs or levers *g h* of a loop-switch, *B*. This loop-switch *B* is adapted, when depressed, to bring the springs or levers *g h* into contact with the contact-points *i k*, and thus include the calling-keys *l m* and the operator's telephone-outfit *n* in circuit between the plugs *c d*. The loop-switch *B* may be made in any desired form. I preferably use a switch, as shown in Fig. 1, provided with a cam-lever, *o*, adapted, when 70 thrown up, to hold the bars of the switch in contact with the contact-points.

In making a connection between subscribers, the operator inserts a pair of plugs in the switches to which the subscribers are connected. The subscribers are thus at once connected through a clearing-out drop. When the loop-key *B* is depressed, a derived circuit is formed, and the current divides, a portion thereof going through the annunciator, and 85 a portion through the telephone-outfit of the operator. It will be seen, now, that, although both instruments—the clearing-out drop and the operator's outfit—are in circuit at the same time, the resistance introduced into the subscriber's circuit is less than when only one of the instruments is in circuit, on account of the derived circuit, which is formed by my system. The clearing-out annunciator being permanently in the circuit of the plugs, the circuit of the subscriber cannot be opened by 90 failure of the points to make contact. An increase of resistance in the derived circuit, caused by a partial failure of the loop-key to make contact, or by other causes, only results 95 100

in sending more current through the other branch of the derived circuit, and does not therefore effect the talking-circuit.

Having thus described my invention, I claim—

1. The combination, with conducting cords and terminal plugs for connecting two subscribers of a telephone-exchange, of a clearing-out annunciator connected permanently in circuit between said plugs, and switching apparatus whereby an operator's telephone may be connected in a derived circuit around said clearing-out annunciator.

2. In a telephone-exchange, the combination, with telephone-lines emanating from a central office, and a branch line containing a signal device, and provided with means for temporarily connecting it at opposite ends with any two of said telephone-lines, of a tele-

phone and switching apparatus whereby said telephone may be connected into a derived circuit around said signal device.

3. The combination, with the telephone-lines and a branch line provided with means for temporarily connecting it at opposite ends with any two telephone-lines, of a signal device, and a telephone and switch, said signal device being connected permanently with the circuit of said branch, and said switch being adapted to connect the said telephone in a derived circuit around the said signal device.

In witness whereof I hereunto subscribe my name this 9th day of February, A. D. 1884.

CHARLES E. SCRIBNER.

Witnesses:

GEORGE P. BARTON,
C. C. SHEPHERD.
